(57) **CLAIM**

The ornamental design for a nozzle for oral irrigator as shown and described.

DESCRIPTION

1. Nozzle for oral irrigator

1.1 front Perspective view

1.2 Rear Perspective view

1.3 Front

1.4 Back

1.5 Left

1.6 Right

1.7 Top

1.8 Bottom

The broken lines in the drawings illustrate portions of a nozzle for oral irrigator that form no part of the claimed design.
